226,039

COMBINED COIN AND MEMO HOLDER

Martin Krone, 60 E. 42nd St., New York, N.Y. 10017

Filed Dec. 21, 1970, Ser. No. 26,580

Term of patent 14 years

Int. Cl. D19—02

U.S. Cl. D74—1

FIG. 1

FIG. 2

FIG. 3

FIG. 4

FIG. 5

FIG. 1 is a front elevational view of a combined coin and memo holder showing my new design;

FIG. 2 is an elevational view of one side thereof, where the side opposite that disclosed is the same;

FIG. 3 is a top plan view thereof;

FIG. 4 is a rear elevational view thereof; and

FIG. 5 is a perspective view showing the bottom thereof.

I claim:

The ornamental design for a combined coin and memo holder, substantially as shown and described.
